COMBINATION SHOWCASE AND COVER FOR THE CONTAINER OF A GUM VENDOR

Larry S. Smith, Collingwood, Ontario, Canada

Application May 11, 1953, Serial No. 24,933

Term of patent 3½ years

(Cl. D52—3)

To all whom it may concern:

Be it known that I, Larry S. Smith, a citizen of the United States of America, resident of the town of Collingwood, in the Province of Ontario, Canada, have invented a new, original, and ornamental Design for a Combination Showcase and Cover for the Container of a Gum Vendor, of which the following is a specification, reference being had to the accompanying drawing, forming part thereof.

Fig. 1 is a front perspective view of a combination showcase and cover for the container of a gum vendor, showing my new design, and

Fig. 2 is a rear elevational view thereof.

I claim:

The ornamental design for a combination showcase and cover for the container of a gum vendor, as shown.
